UNITED STATES PATENT OFFICE.

ROBERT HEAD, OF NEW YORK, N. Y., ASSIGNOR TO HOWE BAUMANN BALLOON CO., OF NEWARK, NEW JERSEY, A CORPORATION OF NEW JERSEY.

TOY BALLOON.

1,201,045.

Specification of Letters Patent.

Patented Oct. 10, 1916.

Application filed June 29, 1914. Serial No. 847,905.

To all whom it may concern:

Be it known that I, ROBERT HEAD, a citizen of the United States, residing at the city of New York, borough of Manhattan, county 5 and State of New York, have invented a certain new and useful Toy Balloon, of which the following is a specification.

This invention is a means for effectively closing the air or gas inlet to inflatable containers, such as toy balloons, the bladders of punching bags, basket balls, foot balls, and various other inflatable devices composed usually of rubber.

The object of the invention is to provide 15 a closure possessing the following functions:—to securely close the neck or tube immediately following the inflation of the container; to retain the inflating medium within said container for an indefinite time 20 without appreciable loss of said medium notwithstanding it is under pressure due to the elastic nature of the container; easy manipulation of the closure even by unskilled operators for the purpose of sealing the inlet as 25 well as for deflating the container whenever desired; economy of manufacture of the closure, and facility in assemblage with respect to the neck or tube of the container.

The salient feature of the invention is a 30 closure positioned externally upon the neck or tube of the inflatable container, said closure embodying relatively movable members for compressing the neck or tube so that its walls will be forced together and deflected 35 into an abnormal position relative to the line of the normal air or gas passage through said neck.

In a preferred form, the closure is composed of sheet metal, one member of which 40 is provided with a pocket and the other member with a part adapted to be received in said pocket, said members being connected by a part constituting a mouth piece. The neck or tube of the inflatable container 45 is fitted between the two members, the edge of said neck or tube passing through the mouth piece so that said edge may, if desired, be expanded around the mouth piece so that the tube or neck will be retained in 50 an expanded condition for the purpose of blowing air easily and freely into the container, the neck or tube being in a free normal condition. After inflating the container, the operator simply presses the two

members together, as a result of which the 55 wall of the neck or tube is compressed and the gripped part is forced into the pocket of one member by the coöperating part of the other member, thus holding the neck or tube so tightly that the inflating medium 60 cannot escape.

Other features and advantages of the invention will appear from the following detailed description.

In the drawings, Figure 1 is a perspective view of the closure device applied to the neck or tube of an inflatable container, such as a toy balloon. Fig. 2 is a plan view of the metallic blank prior to bending the same to form the closure device. Fig. 3 is a perspective view of the closure device removed from the inflatable article. Fig. 4 is a sectional elevation taken longitudinally through the closure device, said figure illustrating the closure device applied to the neck or 70 tube of the inflatable article and showing said neck or tube in a compressed condition so as to preclude the leakage of the inflating medium from the blown up container.

The closure device of my invention embodies coöperating members A B and a mouthpiece C. Said mouthpiece is provided with an opening c, and it is of any suitable form and dimensions; as shown in Fig. 3, the mouthpiece is elongated, having 85 parallel sides and rounded ends, but the shape may be changed as desired.

The members A B are substantially flat plates positioned one over the other and joined at one end thereof by the mouthpiece. The member B is curled at one end so as to form a pocket D, the latter being open at the side facing toward member A, thus producing the throat d. Member A is provided at its free end with a flange E, depending from said member, the lower edge of said flange being doubled upon itself and forming an enlargement e, the diameter of said enlargement being slightly less than the width of the throat or opening d leading to 100 pocket D.

In the manufacture of my device it is preferred to produce it from a single piece of suitable material, preferably metal, and in Fig. 2 there is shown one form of metal 105 blank which is cut or stamped at one operation from sheet metal. As shown in said Fig. 2, the blank F embodies the mouthpiece

C and members A B, the latter being bent or folded on the dotted lines *f*. It is apparent that the blank can be cut out of sheet metal by a suitable die at one operation, and subsequent to the stamping of the blank it is folded on the lines *f* by the same die or by another independent forming die as desired, said folding of the blank resulting in the closure device shown in Figs. 1, 3 and 4 of the drawings.

In Figs. 1 and 4 there is shown an inflatable container consisting of a bag G, provided with a neck or tube *g*, said bag and its neck being composed of elastic material, such as rubber. The bag may be either a toy balloon or a bladder, such as are used in punching bags, basket balls, foot balls, or any other inflatable object.

To use my device it is opened as shown in Fig. 3 and the neck or tube *g* of the inflatable container is slipped between members A B and through the mouthpiece C. It is preferred to stretch the end portion of the tube or neck into lapping relation to the mouthpiece substantially as shown in Fig. 4, and if desired the edge portion of the neck or tube may be stretched around the edge of the closure device so as to be retained in a distended position thereon and to cause the neck or tube to retain the closure device itself on an integral part of the inflatable container. With the members A B in the opened position of Fig. 3 the air passage through the neck of the tube *g* is free and the container may be inflated by placing the mouthpiece to the lips and blowing air through the tube or neck into the container. After the container shall have been inflated to the desired extent the operator presses the members A B of the closure device together, as a result of which the tube or neck is compressed and the flange E deflects the compressed neck or tube into the space of pocket D, whereby the compressed tube or neck is deflected to an abnormal position by the pressure applied exteriorly thereon due to the pressing together of members A and B. The elastic material composing the neck or tube *g* stretches within the pocket D, and the several parts are held or retained in their closed positions by the frictional engagement of the compressed neck with the surfaces of pocket D and the curled edge of flange E. The parts cannot work loose accidentally owing to the fact that the width of the throat *d* is equal substantially to the diameter of the curled edge *e* of flange E, and thus the air passage through the tube or neck is securely closed so that the air will not leak out or permit the container G to become deflated, certain practical tests having shown that the device is efficient in precluding deflation of the container for several days or for an indefinite period of time.

From the foregoing description taken in

connection with the drawings it is apparent that the closure device may be manufactured rapidly and economically by simply stamping the same from sheet metal or other equivalent material, and folding said stamped metal into the form shown in Fig. 3. The device is easily applied to the tube or neck of the inflatable container, and when so applied it is retained in operative relation to the container by the engagement of the neck or tube with said closure device. The tube is kept in an open position at the mouth end so that the object can be inflated by simply blowing air therein. The device is easily operated for the purpose of keeping air within the container, it only being necessary to press the parts A B together. At the same time, the stretched end of the tube or neck can be withdrawn from engagement with the mouthpiece of the closure device, and the latter being in a normal open position, the tube or neck can be withdrawn from the container or the neck can be slipped out of the closure device.

Having thus fully described the invention, what I claim as new, and desire to secure by Letters Patent is:

1. The combination of a closure device embodying relatively movable members and a cross member connecting said relatively movable members, said cross member being provided with an opening, and an inflatable article provided with a compressible neck which passes through the opening of the cross member and between said relatively movable members, the end portion of said neck being expanded into contact with the cross member and forming a mouth-piece whereby air may be blown into the inflatable article.

2. In a device of the class described, a closure device embodying a plurality of relatively movable members and a cross member connecting said relatively movable members, combined with an inflatable article provided with a compressible neck which passes through said cross member, said neck being expanded into contact with said cross member and forming a mouth through which air is adapted to be blown into the inflatable article, and means for locking the relatively movable members when adjusted for compressing the neck of said inflatable article.

3. In a device of the class described, a closure device embodying a plurality of relatively movable members and a cross member connecting said relatively movable members, combined with an inflatable article provided with a compressible neck which passes through said cross member, the free end of said neck being flanged and expanded into contact with said cross member so as to serve as a mouth-piece through which air is adapted to be blown into said inflatable article, and means for locking said relatively mov-

able members upon the adjustment thereof into position for compressing the neck of said inflatable article.

4. In a device of the class described, a closure device embodying a plurality of relatively movable members and a cross member connecting said relatively movable members, combined with an inflatable article provided with a compressible neck which passes through said cross member, said neck being expanded into contact with said cross member and forming a mouth through which air is adapted to be blown into the inflatable article, and coöperating locking means adapted for mutual engagement upon the movement of the relatively movable members into contact with said neck for compressing the latter so as to close the inflatable article against the escape of air.

5. In a device of the class described, a closure device embodying a plurality of relatively movable members and a cross member connecting said first named members at one end thereof, one of said first named members being provided with a pocket and the other having a flange positioned to enter said pocket, combined with an inflatable article provided with a neck which passes through

the cross member and the end of which neck is expanded into contact with the cross member.

6. A closure device for inflatable containers composed of a single piece of material and embodying coöperating members and a mouthpiece, one of said members being provided with a pocket and the other member having a flange positioned opposite to said pocket.

7. A closure device for inflatable containers embodying an open mouthpiece and coöperating members joined at one end thereof by said mouthpiece, the free end of one member being provided with a pocket and the corresponding end of the other member having a flange the edge of which is thickened so as to press a neck or tube of said container into contact with the walls of said pocket.

In testimony whereof I have signed my name to this specification in the presence of two subscribing witnesses.

ROBERT HEAD.
